BY *Victor J. Evans*

ATTORNEY

UNITED STATES PATENT OFFICE

EDWARD F. WITTNER, OF CHICAGO, ILLINOIS

SPARK PLUG

Application filed April 2, 1928. Serial No. 266,776.

This invention relates to certain novel improvements in spark plugs and has for its principal object the provision of an improved construction of this character which will be highly efficient in use and economical in manufacture. In using spark plugs in connection with internal combustion engines or the like difficulty is frequently encountered because of moisture condensation on the outer surface of the plug which allows short circuiting of the plug from the top thereof to the motor frame. It is one of the many objects of this invention to provide a spark plug so constructed as to prevent the admission of moisture or other fluid into the interior of the spark plug and which structure is such as will permit the spark plug to be expeditiously taken apart for cleaning purposes.

Other objects will appear hereinafter.

The invention consists in the novel combination and arrangement of parts to be hereinafter described and claimed.

The invention will be best understood by reference to the accompanying drawings, wherein a preferred form of construction is shown and in which:

Fig. 1 is a side elevational view of my invention; and

Fig. 2 is a sectional detail view of the same.

Referring more particularly to the drawings, my improved spark plug includes a sleeve 10 formed of suitable material such as porcelain or the like. This sleeve 10 has a reduced portion 11 formed at one end thereof outwardly of an enlarged portion 12 which provides a shoulder adapted to abut upon a suitable packing 13 mounted upon a shoulder 14 provided by the plug 15. This plug 15 has its lower portion 16 reduced and threaded for threaded engagement with the opening in the head of an internal combustion engine or the like. Upon the top wall 17 of the shoulder 12 there is likewise provided a suitable packing 18 and threaded into the plug 15 against the ring 18 is a

sleeve nut 19 which co-operates to effect connection between the plug 15 and the sleeve 10. The reduced end portion of the plug 15 carries a finger 20 which is adapted to be bent to dispose its end portion 21 within the center of the plug 15.

The sleeve 10 provides a longitudinal bore 22 in which there is frictionally fitted an electrode 23 adapted to have its end portion 24 disposed a suitable distance from the end portion 21 of the finger 20 for reasons well known in the art. The bore 22 terminates at its upper end in an enlarged bore 25 which extends to the top of the body 10. The upper end of the body 10 embodies a flange 26 and a clamp member 27 formed of pliable material such as soft rubber is adapted to engage this flange so as to prevent displacement of the member 27. The wire leading from the distributor is indicated by 28 in the drawings and as understood in the art, this wire is usually of the so-called stranded type. The upper end of the electrode 23 embodies a conical point 29 which extends into the bore 25. The wire 28 is inserted through an opening 30 in the clamping member 27 and extends down into the bore 25 and if desired, a portion of the insulation on the wire 28 adjacent the end may be cut away so as to disclose the stranded wires as shown in Fig. 2. However, this insulation need not be removed for the end of the wire is arranged such that the conical point 29 will be forced into the end of the wire and engage and distract the strands thereof and cause the wire end to be wedged between the wall of the bore 25 and the point 29. From the foregoing, it is apparent that the connection between the wire 28 and the terminal of the spark plug is concealed within the plug and inasmuch as the clamping member 27 is made of pliable material it is apparent that moisture will be prevented from entering into the plug and thus the detrimental effects thereof will be alleviated.

While I have illustrated and described the preferred form of construction for carrying my invention into effect, this is capable of variations and modifications without departing from the spirit of the invention. I, therefore, do not wish to be limited to the precise details of construction set forth but desire to avail myself of such variations and modifications as come within the scope of the appended claim.

Having thus described my invention, what I claim as new and desire to protect by Letters Patent is:

A spark plug including a sleeve, a plug structure in which one end of said sleeve is mounted, said sleeve having a longitudinal bore extending therethrough and having an enlarged portion at the end thereof opposite the end retained in said plug structure, an electrode extending through said bore having a conical end disposed in said enlarged portion, said enlarged portion being of a diameter substantially equal to the diameter of a wire inserted thereinto whereby when said wire is inserted into said portion the strands thereof will be forced into engagement with said conical end portion to be spread outwardly to wedge said wire in said portion, a flange on said sleeve at the end thereof opposite the end retained in said plug structure, a resilient cap member disposed around said wire and engaging said flange to retain said wire in position and to prevent passage of moisture into said enlarged portion and said bore.

In testimony whereof I affix my signature.
EDWARD F. WITTNER.
